UNITED STATES PATENT OFFICE.

HENRY G. ROTH, OF MINNEAPOLIS, MINNESOTA.

DESIGN FOR A DISPLAY-FIXTURE FOR STORES.

SPECIFICATION forming part of Design No. 36,270, dated March 31, 1903.

Application filed January 5, 1903. Serial No. 137,885. Term of patent 14 years.

To all whom it may concern:

Be it known that I, HENRY G. ROTH, a citizen of the United States, residing at Minneapolis, Hennepin county, Minnesota, have invented and produced a new, original, and ornamental Design for a Display-Fixture for Stores, of which the following is a specification, reference being had to the accompanying drawings, forming part thereof.

10 In the said drawings, Figure 1 is a view in front elevation, and Fig. 2 is a side elevation of the parts shown in Fig. 1.

As shown in the said drawings, the design is made up of several horizontal rows or series 15 of crescent-shaped bodies having their points or prongs turned downward and their sides in tangential contact and a series or top row of crescent-shaped bodies a' having their points turned upward and with the convex 20 surfaces thereof in tangential contact with the convex surfaces of the upper horizontal row of crescent-shaped bodies a . It will also be seen that the crescents a and a' are staggered with respect to each other. Approximately

diamond-shaped filling-pieces b and approximately triangular filling-pieces b' are placed between the convex portions of adjacent crescent-shaped bodies a and a' . These filling-pieces b and b' are colored or shaded, so as to afford a background which will cause the crescents to stand out prominently. 25 30

The above design is especially intended for use in groceries and other stores where canned or bottled goods are to be displayed on shelving. 35

Having thus described my invention, what I claim as new, and desire to secure by Letters Patent of the United States, is as follows:

The ornamental design for a display-fixture for stores, substantially as herein shown 40 and described.

In testimony whereof I affix my signature in presence of two witnesses.

HENRY G. ROTH.
